(57) **CLAIM**

The ornamental design for a luggage, as shown and described.

DESCRIPTION

FIG. 1 shows a front perspective view of a luggage, showing the new design;

FIG. 2 shows a front elevation view thereof;

FIG. 3 shows a rear elevation view thereof;

FIG. 4 shows a right elevation view thereof;

FIG. 5 shows a left elevation view thereof;

FIG. 6 shows a top view thereof; and,

FIG. 7 shows a bottom view thereof.

The broken lines depict portions of the luggage that form no part of the claimed design.

1 Claim, 7 Drawing Sheets
